CLAIM

I claim the ornamental design for a bra with a removable underwire, as shown and described.

DESCRIPTION

FIG. 1 is a perspective view of a bra with a removable underwire of my claimed design, shown in an environment of use on a person;

FIG. 2 is a front view of the bra of FIG. 1;

FIG. 3 is a back view of the bra of FIG. 1;

FIG. 4 is a left side view of the bra of FIG. 1;

FIG. 5 is a right side view of the bra of FIG. 1;

FIG. 6 is a top view of the bra of FIG. 1; and,

FIG. 7 is a bottom view of the bra of FIG. 1.

The broken lines in FIG. 1 showing a person are for the purpose of illustrating environmental structure and form no part of the claimed design. The broken lines in FIGS. 1-7 show portions of the bra which form no part of the claimed design.
